UNITED STATES PATENT OFFICE.

HARRY MENDELSON, OF NEW YORK, N. Y.

REVERSIBLE BUFFER.

1,134,088.

Specification of Letters Patent. Patented Mar. 30, 1915.

Application filed November 23, 1911. Serial No. 661,971.

To all whom it may concern:

Be it known that I, HARRY MENDELSON, a citizen of the United States, and a resident of the city of New York, borough of 5 Manhattan, in the county and State of New York, have invented a new and Improved Reversible Buffer, of which the following is a full, clear, and exact description.

My invention relates to a buffer intended 10 especially for manicuring, and more particularly to a buffer having a reversible buffering block and a detachable handle adapted to be applied to the block with either buffering surface of the block in position for 15 use.

The invention aims to provide an improved buffer of this kind, and especially to provide a reversible buffer of simple construction so constructed that the handle may 20 be readily and quickly applied to and removed from the buffering block to reverse the position of the block with respect to the handle so as to bring either buffering surface thereof into position for use.

25 To these ends, the invention consists in the features of construction and arrangement of parts as hereinafter described and specifically pointed out in the claims.

The accompanying drawings illustrate a 30 typical embodiment of the invention.

In said drawings:—Figure 1 is a perspective view of a buffer showing a buffering block in operative position in a handle of suitable construction; Fig. 2 is a side view of the top 35 of the body of the block before the buffering material is applied thereto; Fig. 3 is a view of one face of the body of the block; Fig. 4 is a sectional view of the block taken on line 4—4 of Fig. 2 and showing a portion 40 of the handle in position as it is about to be applied to the block; Fig. 5 is a transverse sectional view of the body of the block without the buffering material; and Fig. 6 is a similar view but showing the complete block 45 provided with its buffering surfaces.

Referring to the drawings, the buffer block 1 which may be of any desired size and made of any desired material, preferably of wood, is of the usual elongated form 50 having its sides tapered off toward each end. The particular form of block may, of course, be varied. Opposite faces 2 and 3 of the body of the block which are to receive the buffering material are desirably made 55 slightly longitudinally concave as shown, thus providing a block which is thicker transversely to its faces 2 and 3 at the ends

than it is in its middle portion. The sides of the block are formed with a slot or channel 4 extending around the block adjacent each of the faces 2 and 3 for receiving, as shown in Fig. 6, the edge portion of a piece of chamois or kid or similar material 6 which extends over the face of the block to provide a buffering surface, a suitable mass 65 of a soft substance 5 being provided as a filling beneath the material 6. The dimensions of the slots or channels 4 are determined by the nature of the material 6. The edges of the pieces of material forming the buffering surface may be held securely 70 in the slots 4 by suitably filling means such as a piece of braided or twisted silk 7 the thickness of which is sufficient when forced into the slot along with the edge portion of 75 the buffering material to securely hold the same.

For engagement with the handle, the sides of the block between the channels 4 are curved inwardly or hollowed out to provide a guiding and positioning groove 8 with outwardly flaring walls, such groove extending most desirably completely around the block and the width and depth of the guiding groove being greatest at the ends of 85 the block as shown at 10 and decreasing toward the center or middle portion of the block.

The handle 15 comprises a hand grip 16 and block engaging portions extending from 90 the hand grip and adapted to hold the block by engagement in the groove 8. A suitable form of handle is shown in the drawings and is more specifically described and claimed in my U. S. Patent No. 1,014,629, 95 dated January 9, 1912. In this handle the block engaging portions or parts carried by the hand grip 16 are formed of wire bent to provide a closed U-shaped end member 17 adapted to seat in the portions of the groove 100 8 of the buffering block at and adjacent to one end of the block, and separable members 18 to engage in the groove 8 at and near the other end of the block, these separable members being formed to be secured together about the end of the block when the block has been positioned in the handle. As shown, the ends of the separable members 18 carry knobs 19 which are adapted to snap by each other and to interlock one 110 with the other. The engaging portions 17 and 18 of the handle are connected with the hand grip by upwardly and then inwardly extending portions of the wire as

shown and as more fully described in my said patent.

The block is positioned in the handle and removed therefrom by relative endwise movement between the block and the handle, the ends of the separable members 18 of the handle running in the groove 8 of the block during such relative movement. To remove the block from the handle, it is only necessary to release the interlocking ends of the separable members 18 of the handle and then withdraw the block, as by grasping it with the fingers on its opposite buffering faces. To reconnect the handle and block with either buffering surface of the block outermost, the block and handle are brought together with one end of the block entered between the ends of the separable engaging members of the handle and then by relative endwise movement they are positioned as shown in Fig. 1, when by turning the interlocking knobs of the handle past each other the handle may be securely locked to the block and the two members will then be held against relative separating movement.

It will be readily seen that because of the form of the guiding groove 8 with its flaring walls and widths in excess of the width of the engaging members of the handle, the necessity of any considerable degree of care in entering the end of the buffering block between the ends of the separable handle members and in sliding the parts into relative position is entirely avoided. The wide flaring walls of the groove at the ends of the block act to position the entering ends of the handle members as the block and handle are brought together, and also insure the proper engaging position of the engaging members of the handle at both ends of the block when the handle and block are brought to operative position and the separable handle members locked together about the end of the block. It will be observed that the functions of the wide flaring walls of the guiding groove are performed more particularly in the portions of the groove adjacent the ends of the block, and that the narrowing of the groove toward the middle of the block does not, therefore, interfere with the securing of the desired result; and this narrowing of the groove in the central portion of the block is of advantage especially in permitting the block to be made of a minimum thickness through its central portion and in securing the desired form of the groove at the ends of the block without unduly increasing the thickness of the block as a whole.

60 What is claimed is:

1. A buffer comprising in combination a reversible buffering block having buffering surfaces on opposite faces thereof, and a de-

tachable handle, the handle having a hand grip and block engaging portions extending from the hand grip and including separable members for engaging one end of the block, and the block having its surface between its buffering faces formed to provide a guiding and positioning groove with outwardly flaring walls adapted to receive the block engaging portions of the handle, said groove being of a width substantially greater than required for holding the engaging portions of the handle in position when seated therein, whereby the handle may be readily applied to or removed from the block with either buffering surface of the block outermost by a relative endwise movement of the block and handle with the engaging portions of the handle running in the block groove.

2. A buffer comprising in combination a reversible buffering block having buffering surfaces on opposite faces thereof, and a detachable handle, the handle having a hand grip and block engaging portions extending from the hand grip and including separable members for engaging one end of the block provided with locking means for securing said members together about the end of the block, and the block having its surface between its buffering faces formed to provide a guiding and positioning groove with outwardly flaring walls adapted to receive the block engaging portions of the handle, said groove at and near the ends of the block being of a width substantially greater than required for holding the engaging portions of the handle in position when seated therein and decreasing in width toward the middle portion of the block, whereby the handle may be readily applied to or removed from the block with either buffering surface of the block outermost by a relative endwise movement of the block and handle with the engaging portions of the handle running in the block groove.

3. A reversible buffering block having opposite faces provided with buffering material, and having its surface all the way about the block between the buffering faces formed to provide a guiding and positioning groove with outwardly flaring walls adapted to receive the block engaging portions of a detachable handle, said groove being of a width substantially greater than required for holding the engaging portions of the handle in position when seated therein.

In testimony whereof I have signed my name to this specification in the presence of two subscribing witnesses.

HARRY MENDELSONH.
